BRUSH RIGGING

Robert W. Groot, Fort Wayne, Ind., assignor to
General Electric Company, a corporation of
New York

Application November 3, 1944, Serial No. 561,718

6 Claims. (Cl. 171—323)

1

My invention relates to brush riggings and more particularly to a brush rigging adapted to be used with a dynamoelectric machine which rotates bodily.

An object of my invention is to provide an improved brush rigging.

Another object of my invention is to provide improved brush rigging for a bodily rotatable dynamoelectric machine wherein centrifugal force effects on the brush are substantially neutralized.

Further objects and advantages of my invention will become apparent from the following description referring to the accompanying drawing, and the features of novelty which characterize my invention will be pointed out with particularity in the claims annexed to and forming a part of this specification.

In the drawing the figure is a side elevational view of a brush rigging provided with an embodiment of my invention.

In certain types of dynamoelectric machines the entire machine including the stator is bodily rotatable about the axis of rotation of the rotatable member of the machine. With this type construction the brush rigging is subjected to centrifugal forces which may tend to vary the pressure of the brush on the current collector of the machine and produce undesirable sparking at the contact between the current collector and the brush. In my improved construction of a brush rigging adapted for this type use, the action of centrifugal force on the brush is substantially neutralized and in addition the brush holder may be constructed such that variations in the resilient biasing pressure of the biasing spring on the brush for different lengths of the brush as the brush becomes worn may also be compensated when the machine is being bodily rotated. This latter feature, however, may be omitted if desired.

As shown in the drawing the dynamoelectric machine is provided with a rotatable member mounted on a shaft 1 and provided with a current collector in the form of a commutator 2 adapted to be contacted by a contact brush 3. This brush 3 may be secured in any suitable manner, as by a screw 4, to the end of a brush holder biasing and supporting arm 5 which forms part of the brush rigging. As can be readily understood the brush 3 could also be arranged in a conventional box type brush holder and the biasing arm 5 could be arranged in engagement with the upper surface of the brush for biasing it towards the current collector. The brush holder arm 5 is pivotally mounted by a pivot pin 6 about an axis which is substantially parallel to the axis of rotation of the dynamoelectric machine shaft 1. In order to provide the desired pressure of the brush 3 on the commutator 2 a resilient coil spring 7 is

2

arranged to exert a pressure on the brush 3 through the end of the brush holder arm 5. With this type construction centrifugal force will tend to decrease the pressure of the brush 3 on the commutator 2 when the machine including the brush rigging rotates about the axis of rotation of the shaft 1, as centrifugal force will tend to throw the brush 3 and brush holder arm 5 outwardly away from the commutator surface 2. In order substantially to neutralize this action of centrifugal force on the brush pressure, I provide a second arm 8 which extends at an obtuse angle, preferably between 90 and 160 degrees, to the brush biasing and supporting arm 5 and arranged such that the angle A between the second arm 8 and a radius from the axis of the machine to the center of gravity of the weight 9 is between 15° and 60° for the position of the second arm 8 for a new brush, as shown in the drawing. This arm 8 is rigidly secured to the arm 5 and may be made an integral part therewith and also may be provided, as shown in the drawing, with an added weight 9 distributed on the arm and arranged at such a length from the axis of the pivotal mounting pin 6 to provide a component decrease in moment about the axis of this pivot pin with a decrease in length of the brush 3 for substantially neutralizing the action of centrifugal force on the brush and the brush supporting arm. As shown in the figure the angle between the arms 5 and 8 is preferably approximately 150 degrees and the position of the arm 8 for a new brush is about 45° to a radius from the center of the current collector 2 of the machine to the center of gravity of the weight 9 such that variations in the position of the arm 8 for different lengths of the brush 3 and therefore for different weights of the brush 3, will produce a sufficient change in the sine of the angle A between the arm 8 and the radius to the center of the machine from the weight 9 to produce a corresponding relative change in the moment arm of the arm 8 about the axis of the pivot pin 6. In addition, the spring pressure of the spring 7 will decrease as the brush 3 becomes worn and this decrease in pressure also can be compensated for by the proper location of the center of gravity of the arm 8 and the weight 9 such that a component change in the moment of centrifugal force on this arm with a decrease in the length of the brush 3 will increase directly as the force of the biasing spring 7 decreases. This will result in maintaining a substantially constant biasing pressure of the brush 3 on the commutator 2.

The distribution of the center of gravity of the weight 9 and the arm 8, as well as the angle A between the arm 8 and the radius to the center of the machine for a new brush can both be utilized for changing the relative moment of the arm 8 about the axis of the pivot pin 6. A change

in the location of the weight 9 will directly affect the length of the moment arm from the center of gravity to the center of the pivot pin 6, while a change in the angle A will affect the rate of change of the moment arm of the center of gravity of the arm 8 relative to the axis of the pivot pin 6. This relative change is directly proportional to the sine of the angle A and the change in the moment of the balance arm 8 and weight 9 with different positions of the brush arm 5 corresponding to different lengths of the brush 3 is illustrated in the drawing by the difference in the moment arms *a* and *b* which correspond to these moment arms for the weight 9 corresponding to a substantially new brush as shown in solid lines in the figure and a worn brush as shown by the dotted line 10 in the figure. Thus I have provided an improved brush rigging which not only eliminates variations in brush pressure due to centrifugal force effects but also can be used to minimize or eliminate variations in the resilient biasing force on a brush by a biasing spring which results from wear of the brush.

While I have illustrated and described a particular embodiment of my invention, modifications thereof will occur to those skilled in the art. I desire it to be understood therefore that my invention is not to be limited to the particular arrangement disclosed and I intend in the appended claims to cover all modifications which do not depart from the spirit and scope of my invention.

What I claim as new and desire to secure by Letters Patent of the United States is:

1. A brush rigging adapted to be rotated about an axis and including a brush holder having an arm and resilient means operably connected to said arm for biasing a contact brush toward a current collector, means for pivotally mounting said brush holder arm about an axis substantially parallel to the axis of rotation of said brush rigging, and means including a second arm rigidly secured to said brush biasing arm arranged at an angle to a radius from the center of said current collector of between 15° and 60° for a new brush and having a weight distributed thereon to provide a moment about the axis of said pivotal mounting for substantially neutralizing the action of centrifugal force on the brush and said first mentioned brush holder arm.

2. A brush rigging adapted to be rotated about an axis and including a brush holder having an arm for supporting a contact brush, means for pivotally mounting said brush holder about an axis substantially parallel to the axis of rotation of said brush rigging, resilient means for biasing the brush in said brush holder toward a current collector rotatable about said brush rigging axis of rotation, and means including a second arm extending at an obtuse angle between 90° and 160° to said brush supporting arm and rigidly secured thereto arranged at an angle to a radius from said axis of between 15° and 60° for a new brush and having a weight distributed thereon to provide a moment about the axis of said pivotal mounting for substantially neutralizing the action of centrifugal force on said brush supporting arm.

3. A brush rigging adapted to be rotated about an axis and including a brush holder having an arm for supporting a contact brush, means for pivotally mounting said brush holder about an axis substantially parallel to the axis of rotation of said brush rigging, resilient means for

biasing the brush in said brush holder toward a current collector rotatable about said brush rigging axis of rotation, and means including a second arm extending at an angle of substantially 150° to said brush supporting arm and rigidly secured thereto arranged at an angle to a radius from said axis of between 15° and 60° for a new brush and having a weight distributed thereon to provide a moment about the axis of said pivotal mounting for substantially neutralizing the action of centrifugal force on said brush supporting arm and for compensating for variations in pressure of said resilient means on the brush for different lengths of the brush.

4. A brush rigging adapted to be rotated about an axis and including a brush holder having an arm for supporting a contact brush, means for pivotally mounting said brush holder about an axis substantially parallel to the axis of rotation of said brush rigging, resilient means for biasing the brush in said brush holder toward a current collector rotatable about said brush rigging axis of rotation, and means including a second arm extending at an angle between 120° and 160° to said brush supporting arm and rigidly secured thereto arranged at an angle to a radius from said axis of between 15° and 60° for a new brush and having a weight and length to provide a moment about the axis of said pivotal mounting for substantially neutralizing the action of centrifugal force on said brush supporting arm and for compensating for variations in pressure of said resilient means on the brush for different lengths of the brush.

5. A brush rigging adapted to be rotated about an axis and including a brush holder having an arm for supporting a contact brush, means including a pivot pin for pivotally mounting said brush holder about an axis substantially parallel to the axis of rotation of said brush rigging, resilient means for biasing the brush in said brush holder toward a current collector rotatable about said brush rigging axis of rotation, and means including a second arm extending at an obtuse angle between 90° and 160° to said brush supporting arm and rigidly secured thereto arranged at an angle to a radius from said axis of between 15° and 60° for a new brush and having a weight distributed thereon to provide a moment about the axis of said pivot pin for substantially neutralizing the action of centrifugal force on said brush supporting arm and for compensating for variations in pressure of said resilient means on the brush for different lengths of the brush.

6. A brush rigging adapted to be rotated about an axis and including a brush holder having an arm for biasing a contact brush toward a current collector, means for pivotally mounting said brush holder arm about an axis substantially parallel to the axis of rotation of said brush rigging, resilient means for biasing said brush holder arm and brush toward the current collector rotatable about said brush rigging axis of rotation, and means including a second arm extending at an obtuse angle to said brush biasing arm and rigidly secured thereto arranged at an angle to a radius from said axis of between 15° and 60° for a new brush and having a weight distributed thereon to provide a moment about the axis of said pivotal mounting for substantially neutralizing the action of centrifugal force on the brush and said brush holder arm and for compensating for variations in pressure of said resilient means on the brush for different lengths of the brush.
